(57) **CLAIM**

The ornamental design for a vehicle suspension assembly, as shown and described.

DESCRIPTION

This application is related to U.S. patent application Ser. No. 29/655,062, entitled "Vehicle," filed Jun. 29, 2018, the entire contents of which are incorporated herein by reference.

FIG. 1 is a top perspective view of a vehicle suspension assembly. The design includes a mirror image of the embodiment depicted;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The dashed broken lines depict portions of the vehicle suspension assembly that form no part of the claimed design. The dot-dashed broken lines represent boundaries of the claimed vehicle suspension assembly and form no part of the claimed design.
